UNITED STATES PATENT OFFICE.

FREDERICK MORRIS, OF SAN FRANCISCO, CALIFORNIA.

AMALGAMATOR AND SETTLER.

SPECIFICATION forming part of Letters Patent No. 278,035, dated May 22, 1883.

Application filed March 19, 1883. (No model.)

To all whom it may concern:

Be it known that I, FREDERICK MORRIS, of the city and county of San Francisco, State of California, have invented an Improved Amalgamator and Settler; and I hereby declare the following to be a full, clear, and exact description thereof.

My invention relates to certain improvements in amalgamators and settlers, and in the construction thereof, the object of which is to provide a strong and water-tight device which shall be both economical and durable.

The nature of these improvements will hereinafter fully appear, reference being made to the accompanying drawings, in which—

Figure 1 is a perspective view of my device with a portion of the vessel D broken away. Fig. 2 is a vertical section of same.

A represents a wooden platform, having a central vertical post, B, secured to it by bolts b passing down through said post and platform. Around this post, upon the platform, are fitted segmental blocks a, forming a plate or disk which is the bottom of the vessel D. These blocks are nailed down to the platform. The reason for this construction is that the bottom cannot shrink as much as if it were made of straight strips, and it has a tendency rather to tighten in shrinking than to loosen. The sides of vessel D are made of staves d, the lower ends of which are nailed to the periphery of the blocks a, forming the bottom. These staves are secured together by wooden hoops e, tacked to each stave, one hoop covering the joint of the other, and having its own joint at the opposite side.

On the bottom of the vessel D are laid segmental blocks h, or dies, which, by being made shorter than the blocks a, forming the bottom, leave a peripheral channel or groove, f. Their sides are also provided with thin strips whereby they are separated sufficiently to form shallow radiating grooves g.

Upon the top of post B is secured a cap, i, which serves as a step or bearing for a vertical shaft, I, which is journaled therein. Upon this shaft is the cross-frame, J, of the muller, in the arms of which are secured rods K, extending down within the vessel nearly to the blocks h. Upon these rods are loosely fitted the muller shoes or blocks L. These may have

a vertical play upon the rods, and are self-acting, as they cannot fall away because the rods reach nearly to the bottom. They therefore pass along the bottom and adjust themselves vertically on the rods, according to material in the vessel. In order to keep this vertical adjustment unimpaired, I must remove part of the strain from the rods. I therefore connect each muller block or shoe with the cross-arm in advance of it by means of a rod, M, connected by loose links m and screw-eyes n. These latter may be adjusted as the shoes wear. In order to insure the shoes remaining as low down as possible or going down again to their place, I place a weight, o, upon each.

The muller is revolved by the following means: Upon top of shaft I is a crown-gear, P, meshing with a pinion, Q, upon a shaft, R, having a driving-pulley, S. The pinion Q is placed upon a feather on the shaft, and has a collar, q, and a lever, q', secured thereto, in order to throw said pinion in or out of engagement with the crown-gear. This device is for the purpose of settling ore-pulp in order to separate the heavy particles from the mud and slime after the ore has been ground. The revolving muller keeps the pulp in a constant state of agitation, in which the heavier particles separate and settle, and the waste material rises and must be drawn off. The revolution of the muller causes the waste after separation to be gradually forced to the center, and it is here that I allow it to escape. I make two holes, w, through the post and platform, which carry off the waste into a channel, x, under the platform. These holes are not made in the very top of the post, but in small ledge cut out nearly at the top, as shown. No sand will get in the step i. These escapes are easy to make, and being right at the center and top, none but the worthless part, which has been fully separated and has risen to the top, will be discharged.

The whole device is simple and economical, and is put together in such manner as to render it water-tight and durable.

Having thus described my invention, what I claim as new, and desire to secure by Letters Patent, is—

1. The platform A and central post, B, secured thereto by bolts b, in combination with

the segmental blocks *a*, fitted around the post and nailed to the platform, and the staves *d*, nailed to the rims of the block and secured by wooden hoops *e*, said blocks and staves forming a vessel, *D*, upon said platform and around said post, substantially as and for the purpose herein described.

2. The platform *A* and post *B*, secured thereto, the vessel *D*, formed upon said platform, around the post, and the die-blocks *h* in said vessel, in combination with the muller cross-frame *J*, journaled on said post, the rods *K*, the muller-shoes *L*, loosely fitted on the rods, and the rods *M*, connecting each shoe with the arm *15* of the muller-frame in advance, substantially as and for the purpose herein described.

3. The platform *A*, post *B*, with its discharge-

holes *w*, and the vessel *D*, built upon the platform, around the post, as herein described, in combination with the die-blocks *h*, the muller cross-frame *J*, having rods *K* and vertically-adjustable shoes *L*, connected each with a preceding arm of the cross-frame, and the means for revolving said muller and shoes, consisting of the vertical shaft *I*, journaled in post *B*, *25* and having crown-gear *P*, and the driving-shaft *R*, having pinion *Q*, meshing with said crown-gear, substantially as herein described.

In witness whereof I hereunto set my hand.

FREDERICK MORRIS.
